UNITED STATES PATENT OFFICE

MILTON J. NOUSLAKIS, OF BINGHAM CANYON, UTAH

PARACHUTE FOR AEROPLANES

Application filed August 3, 1931. Serial No. 554,726.

My invention relates to aeroplanes and has for its object to provide a new and efficient parachute for lowering the plane to the earth when the motor has stalled or other accidents 5 have happened to make it a necessity to land without power and without gliding.

A further object is to provide a parachute for aeroplanes which is carried medially of the wings or in the fuselage, and which parachute will be opened by the pilot upon necessity, and which parachute when released will be mechanically and instantaneously thrown up and out from the container.

A still further object is to provide a parachute which when released will open at once and one which will be positive in its operation, due to the fact, that the chute is thrown up and out from the container with sufficient velocity to practically open the chute at once.

These objects I accomplish with the device illustrated in the accompanying drawing in which similar numerals and letters of reference indicate like parts throughout the several views and as described in the specification forming a part of this application and pointed out in the appended claims.

In the drawings in which I have shown the best and most preferred manner of building my invention

Figure 1 is a side elevation of a plane with my device mounted thereon.

Figure 2 is a plan view of a plane with my device thereon, part of one wing removed.

Figure 3 is a section of the cover and a side 35 elevation of the pivot joint and springs for the opening bar.

Figure 4 is a section of the free end of the bar with the parachute attachment rod therein.

Figure 5 is a plan view of the box with the chute folded therein the opening bars and rods in place and the lid open.

Figure 6 is a plan view of the pivot joint and the elevating bar control springs enlarged to show the construction with the cover sectioned.

In the drawing I have shown the wings of the plane as A, the fuselage as B, and medially between the wing tips I provide a para- 50 chute containing box C. The box C may be

formed either in the wings or in the fuselage, depending upon the type of plane to which the device is attached.

The box C is provided with a spring controlled lid 1, which lid is pivotally or hinged- 55 ly secured to the back edge of the box by the hinge 2 and is normally held closed by the control rod and hook 3. The spring 4 holds the lid open when the hook is released. Notches 5 are cut in the front and the two 60 sides of the box to receive the free ends of the elevating bars 6, 7, and 8. The parachute D is provided with three attachment rods 9, 10 and 11, adapted to be inserted into the hollow 65 ends of the bars 6, 7 and 8 respectively. The rods are placed in the ends of the elevating bars and are easily and slidably removable therefrom, being only to open and elevate the perimeter of the chute. The rods are secured to the perimeter of the parachute by any suitable means such as sewing a ring 12 on the 70 end of the rods to the perimeter of the parachute. The elevating bars 6 and 7 are attached to the plane wings A by forming the ends 13 of the rods into a hinge joint 14 and securing the joint 14 to a hinge plate 15 by a pin 16. The bar 8 is attached in front of the plane the necessary distance by an extension support bracket 17 secured to the plane by one end and supported by the bracket 18. 80 The end 19 of the bracket 17 is turned up to form the spring holding member and the end of the bar 8 is made similar to the ends of the bars 6 and 7, being a hinge joint 20 attached to the bracket 17 by a hinge joint 21 and a hinge pin 22.

The ends of the plates 15 are bent up to provide spring engaging and hinge ends 23.

Each bar is provided with a yoke 24, which yoke carries spring holding arms 25, and springs 26 and 27 are attached to the arms 25 and to the ends 23 of the plates 15 and to the end 19 of the bracket 17. The springs will be made sufficiently strong to raise the rods and bars from the box to a vertical position at the 95 same time raising the parachute with the rods.

The dotted lines in Figure 3 show the bars raised to vertical by the springs 26 and 27.

A cover F is provided to cover the springs and hinges to prevent freezing or clogging 100

by ice or snow and said cover is hinged to the end of the plate 15 and to the bracket 19 by the pin 30 in the hinge 32.

Wires 31 brace the bracket 19 to the wings 5 of the plane.

The operation of my device is as follows:

To open the parachute the aviator releases the catch hook 3 and the power of the springs 26 and 27, and the spring 4 will throw the lid 10 1 open at the same time raising the rods 6, 7 and 8 and their rods 9, 10 and 11. These rods are controlled by springs and will be raised instantaneously, at the same time raising the parachute from the container box and throwing 15 it upward into the air currents, which air currents will completely open the parachute. The rod 8 being in front of the plane throws the parachute in such a position that the air currents will naturally fill the parachute as 20 the plane is traveling down through the air.

Having thus described my invention I desire to secure by Letters Patent and claim:

1. In a device of the class described the combination of a box mounted on the top of 25 an aeroplane; elevating bars hingedly connected one, to each plane wing and one, to an extension in front of the plane; springs to actuate said bars and raise them when their free ends have been released; a parachute secured to the plane by the usual cords and having attachment rods secured to the perimeter thereof, said rods to fit into the ends of the elevating bars and to slide therefrom when the parachute is opened; and means to release 30 the lid of the box to allow said bars to raise therefrom.

2. In a device of the class described the combination of a box mounted in the top of an aeroplane; a parachute carried in said 40 box having the usual cords connecting the parachute to the the aeroplane; attachment rods secured to the perimeter of said parachute; elevating rods secured pivotally to the wings, and one elevating rod secured pivotally in front of the plane; springs carried on each rod to raise the rods to a vertical position, one end of the springs being secured to the plane and the ends of the rods being hollow to receive the attachment rods 45 of the parachute; and means to open said box to release said elevating rods and the parachute from the box.

In testimony whereof I have affixed my signature.

55 MILTON J. NOUSLAKIS.
